METHOD OF MAKING PILE FABRIC AND PILE FABRIC MADE THEREBY

Nicholas Corey, Yonkers, N.Y., and Charles H. Andrews, Pompton Plains, N.J., assignors to The Beattie Manufacturing Company, Little Falls, N.J., a corporation of New Jersey

Filed Sept. 14, 1959, Ser. No. 839,652
5 Claims. (Cl. 139—396)

The present invention relates to an improved method of forming pile fabric and more particularly to an improved pile fabric formed thereby.

In making pile fabric on Axminster looms, it has been the practice to use a comb to form the pile loops or to insert pile wires beneath the pile yarn to form the necessary pile loops. Pile fabric has also been made on a noseboard loom by inserting individual spools with protruding ends for each dent into the base fabric, carrying the ends over the noseboard, then severing the ends by scissor action on the surface thus producing one row of tufts for three weft insertions. In using pile wires, it is necessary to provide a pile wire assembly which, of course, increases production costs and is space consuming.

Heretofore, in producing carpets of pile material, two or more weft insertions between a like number of warp sheds have been necessary, one while the pile is on the surface and one or more while the tuft is bound to the base fabric.

An object of the present invention is to provide an improved method of making a pile fabric and an improved fabric.

Another object of the present invention is to provide an improved method of weaving a loop or cut pile fabric on an Axminster loom which eliminates the necessity of using either pile wires or a comb.

Another object of the invention is to increase the ratio of face material in the fabric to backing fabric thus providing a more economical carpet of comparable wearing quality and face density and at the same time increasing production, reducing weft and other backing material. This is accomplished by inserting two rows of tufts for three consecutive picks as opposed to one row for two or more picks achieved in prior practice.

Another object is to provide a means of producing alternate rows longitudinally in a carpet either of the same or varying heights.

Another object is to provide a better bind of the tufts into the base fabric by raising two of the warp ends over each tuft on at least one of each tuft's point of binding.

Another object is to permit the heights of the loops to be greater, with the least consumption of yarn by varying the horizontal heights of the weft picks longitudinally.

A further object of the present invention is to provide an improved mechanism for performing the method and for making the pile fabric of the present invention.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

FIG. 1 is an exaggerated sectional view showing a pile fabric formed in accordance with the present invention;

FIG. 2 is a sectional view similar to FIG. 1 with the binder warps and stuffer yarn removed showing the relationship between the pile yarn and the wefts;

FIG. 3 is a sectional view similar to FIG. 1 with the

2

pile yarn removed showing the relationship between the binder warps, the stuffer yarn and the wefts;

FIG. 4 is a diagrammatic view showing the first step in the formation of the pile fabric of the present invention;

5 FIG. 5 is diagrammatic view showing the second step in the method;

FIG. 6 is a diagrammatic view showing the third step in the method;

10 FIG. 7 is a diagrammatic view showing the fourth step in the method;

FIG. 8 is a diagrammatic view showing the fifth step in the method;

15 FIG. 9 is a diagrammatic view showing the final step in the method;

FIG. 10 is a diagrammatic view of a modification of the present invention showing a mechanism for forming a loop of lower height; and

20 FIG. 11 is a diagrammatic view similar to FIG. 10 showing the mechanisms in position to form a loop of greater height.

The method of forming the improved pile fabric of the present invention is shown in FIGS. 4 through 9. The loom comprises a noseboard 1 having an upstanding portion 2 over which the yarn is forced by means of the usual reed 3, which beats the yarn over the upstanding portion 2. The various yarns are separated by heddles (not shown) to form the usual shed. In the drawings, the pile yarn 10 is over the noseboard, while binder yarns 11 and 12 and stuffer yarn 13 lie in suitable slots in the noseboard.

30 The first step in the method is shown in FIG. 4. The shed is formed by moving the pile yarn 10 and the binder warp 11 up and moving the binder warp 12 and the stuffer yarn 13 down. It will be understood that it is not essential to use the stuffer yarn 13 and it is within the scope of the present invention to form a pile fabric without stuffer yarn.

35 A first shot of weft 15 is inserted in the shed as shown in FIG. 4. In the drawing the weft is shown as a double strand shot; however, it will be understood that it is within the scope of the present invention to use a single strand weft or a multiple strand weft.

40 As shown in FIG. 5, the weft 15 is beat by the reed 3. However, the reed 3 does not force the weft 15 over the upstanding portion of noseboard 1 but lays it in front of the noseboard 1 since the reed does not advance to its full forward position.

The shed is then reversed as shown in FIG. 6. The pile yarn 10 and the binder warp 11 is lowered and the stuffer yarn 13 and the binder warp 12 is raised. A second weft 16 is inserted in the shed. The reed 3 beats the second weft over upstanding portion 2 of the noseboard 1 as shown in FIG. 7. This action also forces the first weft 15 over the upstanding portion 2 of the noseboard 1 and there is a tendency for the second weft

55 16 to move underneath the first weft 15 due to the different tensions of the individual warp ends. When the second weft 16 is beat over the noseboard, a first loop L is formed, as shown in FIG. 7. The pile yarn forms a loop L by being forced over the noseboard by weft 16 while the warp ends remain in the slots in the noseboard. This is accomplished by the pile yarn being larger thus preventing its entrance into the slot and also being drawn differently in the reed to free it from the slot to the solid portion of the noseboard. The loop L has weft 15

60 65 beneath it and weft 16 on one side. As is common in such machines, the binder and stuffer warps are placed in the slots in the noseboard and any suitable means may be used to apply pressure to the fell of the cloth to prevent them from being pulled out of the slots.

70 The next step involves lowering of the stuffer yarn 13 and relaxing the tension on the pile yarn by any suit-

able means as shown in FIG. 8. A third weft 17 is inserted in the shed which is beat over the upstanding portion 2 of the noseboard 1 as shown in FIG. 9. The relaxing of the tension of the pile yarn 10 permits a portion of the yarn to be forced over the noseboard with the third weft 17 to form a second loop M (FIG. 9). The second loop M is held between the second weft 16 and third weft 17. It will be observed that there is no weft beneath the loop M so that a saving in material is accomplished and production is increased.

The cycle is then repeated to form the pile fabric shown in FIGS. 1 through 3.

It will be noted from FIG. 2 that the loops M are slightly shorter than the loops L. However, loop M does not have a weft therein but is held in place by the second weft 16 and third weft 17 which squeeze the lower portions of the loop M together to hold it securely in place. Hence, it will be seen that since the loops M do not have any weft there beneath, a lesser amount of weft thread is used without sacrificing the appearance of durability of the finished fabric.

The loops L are held in place by the coaction of wefts 17 and 16 from the outside and the weft 15 which is within loop L.

As shown in FIG. 3, binder warp 12 goes over the wefts 17 and 16 and under weft 15 while the other binder warp 11 goes over weft 15 and under wefts 16 and 17. The stuffer yarn 13 goes under wefts 15 and 17 and over weft 16 in the usual manner.

In order to vary the height of the loops M, the noseboard 1 may be provided with a removable bar 20, as shown in FIG. 10. With this bar so in place, the loop M is of a lesser height. However, if this bar is removed, as shown in FIG. 11, the loop M will be of greater height since more pile yarn will be forced on upstanding portion 2 of the nose-board 1 by the reeds.

Another manner in which the height of the loops M may be varied is by regulating the tension on the pile yarn. The more tension on the pile yarn, the less height the loop M will have because less yarn is forced over the nose-board 1. However, less tension on the pile yarn will increase the size of loop M since more yarn will be forced over the nose-board 1.

It will be seen that the present invention provides an improved method of forming an improved pile fabric without the necessity of using pile wires or combs and which will utilize a lesser amount of yarn for the wefts without affecting the appearance or durability of the pile fabric.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described our invention, we claim:

1. The method of forming a pile fabric which comprises lowering the pile yarn and a first binder warp, raising a second binder warp, inserting a weft of a first group of wefts in the shed, raising the pile yarn and said first binder warp, lowering said second binder warp, inserting a first weft of a second group of wefts in the shed, beating said first weft of said second set for a predetermined distance, lowering said first binder warp and said pile yarn, raising said second binder warp, inserting a second weft of said second group in said shed, beating said second weft for a greater distance than said first weft thereby moving the first weft forward to form a first loop between the weft of the first group and the second

weft of the second group, inserting a third weft of the second group in said shed, beating said third weft to form a second loop between said second and third wefts.

2. The method of forming a pile fabric which comprises lowering the pile yarn and a first binder warp, raising a second binder warp, inserting a weft of a first group of wefts in the shed, raising the pile yarn and said first binder warp, lowering said second binder warp, inserting a first weft of a second group of wefts in the shed, beating said first weft of said second group for a predetermined distance, lowering said first binder warp and said pile yarn, raising said second binder warp, inserting a second weft of said second group in said shed, beating said second weft for a greater distance than said first weft thereby moving the first weft forward to form a first loop between the weft of the first group and the second weft of the second group, slackening the tension on said pile yarn, inserting a third weft of the second group in said shed, and beating said third weft to form a second loop between said second and third wefts.

3. The method of forming a pile fabric which comprises lowering the pile yarn, a first binder warp and a stuffer yarn, raising a second binder warp, inserting a weft of a first group of wefts in the shed, raising the pile yarn and the first binder warp, lowering the second binder warp, inserting a first weft of a second group of wefts in the shed, beating said first weft of said second group for a predetermined distance, lowering said first binder warp and said pile yarn, raising said second binder warp and said stuffer yarn, inserting a second weft of said second group in said shed, beating said second weft for a greater distance than said first weft thereby moving the first weft forward to form a first loop between the weft of the first group and the second weft of the second group, lowering said stuffer yarn, slackening the tension on said pile yarn, inserting a third weft of the second group in said shed, and beating said third weft to form a second loop between said second and third wefts.

4. A pile fabric comprising a pile yarn, first binder warps and second binder warps, said pile yarn forming first and second sets of pile loops, the first set of pile loops being held in place by spaced wefts, said second set of pile loops being held in place by adjacent wefts, a weft below said first set of pile loops and interposed between the spaced wefts holding said first set of pile loops in place, said first binder warps underlying the adjacent wefts which hold the second pile loops in place and overlying the weft below the first set of pile loops and the second binder warps overlying the adjacent wefts which hold the second set of pile loops in place and underlying the weft below the first set of pile loops.

5. A pile fabric as claimed in claim 4, wherein stuffer yarn is provided, said stuffer yarn underlying the weft below the first set of pile loops and one of the adjacent wefts which hold the second set of pile loops in place and overlying the other of said adjacent wefts which hold the second set of pile loops in place.
